UNITED STATES PATENT OFFICE.

LOUIS T. WEISS, OF BROOKLYN, NEW YORK, ASSIGNOR TO RELIANCE BALL BEARING DOOR HANGER COMPANY, OF NEW YORK, N. Y., A CORPORATION OF NEW YORK.

DEVICE FOR OPERATING SLIDING DOORS.

1,272,160.

Specification of Letters Patent.

Patented July 9, 1918.

Application filed October 19, 1917. Serial No. 197,383.

To all whom it may concern:

Be it known that I, Louis T. Weiss, a citizen of the United States, and residing in the borough of Brooklyn of the city of New York, in the State of New York, have invented certain new and useful Improvements in Devices for Operating Sliding Doors, of which the following is a specification, reference being had to the accompanying drawings, forming a part hereof.

This invention has for its object to provide improved devices for the operation of sliding doors, such as elevator doors, whereby the doors can be opened easily from one side, shall close automatically when released by the operator, and shall be locked in closed position so that they cannot be opened from the other side. The invention, which is applicable to a single sliding door, to a multiple door opening from one side, and to a multiple center opening door, will be more fully explained hereinafter with reference to the accompanying drawings in which it is illustrated in its application, in a practical form, to a multiple door opening from one side.

In the drawings,—

Figure 1 is a view in elevation illustrating the application of the invention to a door.

Figs. 2 and 3 are detail views, on a larger scale, showing the locking latch indicated in Fig. 1.

Fig. 4 is a detail view in section of the lower end of the cylinder check shown in Fig. 1.

Fig. 5 is a detail view showing an embodiment of the invention slightly different from that shown in Fig. 1.

In the embodiment of the invention illustrated in Fig. 1, the wall *a* has secured thereto a track on which the sliding door *c* is supported in any convenient manner as by a carrier *c'*.

A bellcrank lever *d*, *d'*, is pivotally mounted on a suitable bracket *d*², secured to the wall, and is connected at one end with one leaf *c*⁴ of the sliding door and at the other end with a plunger by which the closing movement of the door is effected. The longer arm *d* of the bellcrank is provided with a suitable handle as hereinafter described, through which pressure may be applied by the operator's hand to unlatch the

door, when it is closed, and to impart to the door its opening movement.

The other arm *d'* of the bellcrank lever is connected to the means by which pressure is applied automatically to the door, through the bellcrank lever, to close it when the pressure of the operator's hand is removed from the handle. As shown, in Fig. 1, the arm *d'* is pivotally connected to the upper end of a plunger *e*, which has a sliding fit in a cylinder *f*. The latter is pivotally mounted, preferably by a ball and socket joint *f'*, on a bracket *f*² which is secured to the wall or casing of the elevator car or shaft. The cylinder *f* acts not only as a guide for the plunger *e* in its movements, but it operates as a check to cushion the downward movement of the plunger, which is heavy enough to effect the closing of the door when the operator's hand is removed from the handle. The lower end of the cylinder *f* is therefore closed by a head *f*³ which is provided with an air vent *f*⁴, controlled by a screw valve *f*⁵ and equipped with a muffler *f*⁶. In order that the opening movement of the door, effected by the operator, may have as little resistance as possible, the head *f*³ is also provided with a check valve *f*⁷ which permits the air to enter freely during the upward movement of the plunger, but prevents the escape of air during the downward movement of the plunger and compels all of the air to pass through the vent *f*⁴.

In Fig. 5 the long arm *d* of the operating lever is shown as extended beyond its pivot by a short arm *d*⁵ which is connected at its extremity with the plunger *e*, by a chain *d*⁶ which passes over the guide wheels *d*⁷. The flexibility of the chain permits the cylinder *f* to be mounted upon a fixed bracket *f*⁸, instead of being pivotally mounted, as shown in Fig. 1.

Connection between the bellcrank and the door *c*⁵ is effected by a link *d*⁸, which is pivoted to the long arm *d* of the bellcrank at one end and with the door at the other end. The long arm *d* of the bellcrank has a longitudinal slot *d*⁹ which engages a pin *c*² carried by the door. This slot has a weighted latch *g*, provided with a handle *g'* and with a notch *g*² for coöperation with the pin *c*², is pivoted upon the lever *d*, as

at g^3 , and has a pin-and-slot connection therewith, as at g^4 , to limit the movement of the latch. The latch is overbalanced by the handle g' so that it stands normally in the position shown in Fig. 2, with the pin c^2 engaged by the notch g^2 , thereby locking the door against movement. The pressure of the operator's hand upon the handle g' , in a direction to open the door, immediately 10 disengages the latch from the pin c^2 and permits the door to be opened against the weight of the plunger. When the pressure of the operator's hand is removed from the handle, the plunger will immediately move 15 both doors to their fully closed position and the pin c^2 will be engaged by the latch g^2 , which is suitably beveled to permit the necessary movement of the latch to be effected by the pin.

20 The operation of the improved devices will now be understood without further explanation. It will also be understood that details of construction and arrangement of the operating devices may be varied to suit 25 different conditions of use and that the in-

vention, except as pointed out in the claims, is not to be limited to the precise construction and arrangement shown.

I claim as my invention:

1. An operating device for sliding doors, 30 comprising a lever pivoted upon a fixed point, one arm of said lever having a longitudinal slot in engagement with a pin on the door to permit the movement of the door with the lever and a handle pivoted on the 35 lever and having a notch for coöperation with the pin on the door.

2. An operating device for sliding doors comprising a lever pivoted upon a fixed point, one arm of said lever having a longitudinal slot in engagement with a pin on the door to permit movement of the door with the lever, a handle pivoted on the lever and having a notch for coöperation with the pin on the door and a weighted plunger connected to the other arm of said lever. 40 45

This specification signed this 18th day of October, A. D. 1917.

LOUIS T. WEISS.
